UNITED STATES PATENT OFFICE.

JOSEPH W. TAGGART, OF WATERTOWN, NEW YORK.

PAPER-BAG-BOTTOMING MACHINE.

Application filed November 23, 1921. Serial No. 517,261.

To all whom it may concern:

Be it known that I, JOSEPH W. TAGGART, a citizen of the United States, residing at Watertown, in the county of Jefferson and 5 State of New York, have invented certain new and useful Improvements in Paper-Bag-Bottoming Machines, of which the following is a specification.

This invention relates to a machine for 10 slitting, pasting and folding the bottom ends of paper bags, and has for its object to provide novel and simple means for carrying out this work.

Heretofore bottoming machines of the 15 class were equipped with pasting mechanisms which as a rule were geared to the main machine in a manner to effect the perfect synchronizing of the bag feeding and pasting parts. The bags to be operated 20 upon by the machine are generally in the form of flat paper tubes and these are usually fed into the machine by an operator with such regularity that as each tube progresses to a certain point, a rotary or other 25 pad applies the paste to the bottom end flaps, after which the tubes are carried forward to a point where the said flaps are folded and the finished bags are discharged from the machine. As long as the operator 30 maintains a steady and regular feeding of the tubes, the automatic pasting and other parts perform their work perfectly without soiling or otherwise injuring any of the tubes and without loss of production of the 35 finished bags. When, however, the operator misses feeding one or more of the tubes without stopping the machine, the pasting pad operating in synchrony with the drum which carries the tubes, upon arriving at 40 the pasting position daubs the paste upon the exposed face of the drum. Unless this paste is quickly removed from the drum before the feeding of the tubes is resumed, a dozen or more of the succeeding tubes become smeared and fouled by contact with 45 the paste on the drum and are rendered unfit for commercial use. In most cases when the tubes are sent through the machine while the drum is fouled with the paste, the tubes 50 adhere to the drum and become torn and effect the clogging of the machine. This not

only results in the destruction of the tubes but also necessitates the shutting down of the machine and the consequent loss of time and production. The object of the present 55 invention is to obviate the aforesaid troubles and losses and to provide novel, simple, effective and automatic means for preventing the paste pad from making contact with the drum whenever the regular feeding of 60 the tubes is interrupted. To this end my invention consists of the features and parts shown in the accompanying drawings and set forth and claimed in the annexed specification.

In the accompanying drawings, Figure 1 is a side elevation of a bottoming machine to which my improvement is applied. Figs. 2, 3 and 4 are detailed views of the rocking lever and related parts which control 70 the paste pad. Fig. 5 is a front end elevation of the machine with certain parts omitted. Fig. 6 is a top plan view of the rocking lever and related parts. Fig. 7 is a view of one of the paper tubes after the same 75 has been slit. And Fig. 8 is a fragmentary view of the partially folded bottom as it appears just before and immediately after the pasting operation.

In the drawings, 2-2' represent the 80 spaced preferably annular frame portions of the machine which are mounted vertically parallel to each other upon legs 2'. Each of the sections of the frame are braced by a horizontal girder 2", which supports 85 the main drum 3, the latter being rigid on a shaft 3', whose opposite ends are journaled in bearings 3", which are secured to the girders 2". The drum 3 is employed for carrying the paper bags 4 (see full and dotted lines in Figs. 1, 2 and 7) through the 90 machine while the bottoms of the bags are being operated upon. 5 represents the operator's table, which is supported by the frame sections 2-2'. The bags when 95 brought to the machine are in the form of flat paper tubes 4 having open ends (see Fig. 7). These tubes are stacked upon the horizontal top of the table 5, and are fed one at a time in close order into the machine. The tubes 4 are first inserted 100 between a pair of feed-rolls 6-6', from which

they pass between slitter rolls 7—7', for slitting the bottom ends, as shown at 4' in Fig. 7, for providing the usual foldable end flaps 4^a and 4^b. The roll 7 is provided with 5 a sharp spur 7^a, which pierces the two flaps and tends to guide the bottom end of the tubes downwardly and thence between the roll 7 and the drum 3. This spur retains its hold upon the flaps until they emerge 10 clear of the said roll and drum, at which point the flap 4^a springs away from the spur and gravitates toward the drum. This action is quickly followed by the release of the flap 4^b from the spur. The partial folding 15 of the bottom end of the tube immediately follows the release of the flaps from the spur 7^a. 8 represents a small roller (see Figs. 1 and 5) whose opposite ends are provided with similar projecting annular 20 flanges 8', the said roller being mounted on a shaft 8^a, which is journaled in the forked end 9 of a rod 9'. The opposite end of the rod 9' is rigidly connected to a rock-shaft 9^a, which may be journaled in the frame 25 sections 2—2'. The roller 8 performs two functions: the first being to successively engage and press, and hold the flaps 4^a and 4^b against the drum 3, while the opposite lateral bottom end portions of the tubes are being 30 folded diamond-shape, by a pair of conical rollers 10, the latter being mounted on a shaft 10', which is supported by similar brackets 10^a carried by the frame sections 2—2'. In order to carry out this work, the 35 roller 8 is swung outwardly as each tube emerges from the roll 7, from the full line position to the right-hand dotted position, shown in Fig. 1. This movement of the roller 8 is accomplished by the rocking of the shaft 9' by means of a lever 9^b, which is rigid to the said shaft and extends forwardly and downwardly across a constantly driven horizontal shaft 11, upon which is mounted a single-throw cam 9^c, which lifts 40 the rod 9' and effects the aforesaid outward movement of the roll 8. The cam 9^c is positioned to time the outward swinging of the roll 8 slightly in advance of the release of the flap 4^a from the spur 7^a, as described. 45 As the cam 9^c moves away from the rod 9', the roller 8 gravitates toward the left and forces the flap 4^a against the drum. The shaft 11 carries an arc-shaped paste pad 11', which receives fresh paste from a roller 50 12 once each revolution, the said roller being supported by a shaft 12', and being rotated in a pan 12^a which contains the paste. The pad 11' is mounted on a radial arm 11^a, which is provided with a relatively broad 55 transverse slot 11^b, through which the shaft 11 passes. The rotation of the shaft 11 rotates the pad 11' as from the positions shown by full lines to that shown by the dotted lines in Fig. 1, for applying the paste 60 received from the roll 12 to the flaps 4^a and 4^b of the bag immediately following the partial folding of the bottom end by the conical rolls 10. All the rotating parts hereinbefore referred to are driven simultaneously by gears which are connected in a vertical train, indicated by dotted lines at the right in Fig. 5, the said gears being given prime numbers which identify the parts which they operate. The paste pad 11' is driven by a pair of wedges 13 and 13', which are disposed in the slot 11^b, at the opposite sides of the shaft 11. The said wedges being connected by pins 13^a, to one end of a sleeve 14, which is movable lengthwise on the shaft 11, for simultaneously effecting the engagement and disengagement of the said wedges with the opposite ends of the slot 11^b. The reciprocation of the sleeve 14 and the wedges 13—13' correspondingly moves the pad 11' towards and away from the drum 3 and the roll 12, 70 as shown by the full and dotted lines in Figs. 1, 4 and 5. The opposite end of the sleeve 14 is provided with an annular head or flange 14', and the said end is provided with an enlargement which is counterbored 75 at 14^a, to receive a spring 14^b, which normally exerts its tension for holding the sleeve and the wedges 13—13' in the normal operating position shown by the full lines in Figs. 1 and 5 and by the extended dotted 80 lines in Fig. 2, in which position the paste pad 11' is fully extended and alternately receives the paste from the roll 12 and applies the same to the flaps 4^a—4^b. 11^c represents 85 a collar which is rigid to the shaft 11 and against whose inner end a spring 14^b bears. The flange 14' is bored out to receive and is 90 slidably longitudinally upon the collar 11^c, and the sleeve is driven by the shaft 11 and collar 11^c through a key x, as best seen in 95 Fig. 1. 14^c represents a short sleeve which is rigidly mounted on the flange 14', and is provided with an extended cam portion 14^d, which faces the pad 11'. 15 represents a 100 vertically disposed lever, which is pivoted at 110 15' in a yoke 15^a, the latter having a reduced threaded portion 15^b, which passes through an upright supporting bracket 15^c, thence through the horizontal girder 2^b, and is held 105 in place by nuts 15^d. The lower end of the lever 15 is normally disposed in the path of the cam 14^d, and is rocked on its pivot by the said cam, as shown by the full and dotted lines in Figs. 3 and 5, when the tubes 4 are 110 being regularly fed into the machine, and while the roller 8 and the paste pad 11' are performing their normal functions. The lower end of the bracket 15^c overlaps and guides the lever 15 and the upper end of 115 said bracket engages and guides the upper end of said lever. 16 represents a horizontally disposed latch-bar, which is pivoted at 16' to the top end of a bracket 16^a, the latter being mounted on the girder 2^b parallel 120 to the bracket 15^c. The free end of the latch 125 16' 130

16 is positioned above and clear of the top end of the lever 15 and is held in its normal position, shown by the full lines in Figs. 1, 2, 3 and 5 by a counter-weight 16^a disposed at its opposite end. The latch 16 is compressible, as best shown by the dotted lines in Fig. 1, for positioning its free end between the top end of the lever 15 and the adjacent end of the bracket 15^c, for preventing the rocking of the lever 15 by the cam 14^a, as best shown in Fig. 4. The lever 16 is depressed by a finger 17, which is rigid on the top end of a rod 17', the latter being supported and guided by a lug of the bracket 16^a. The lower end of the rod 17' is pivoted to one end of a horizontal rod 9^a, whose opposite end is rigid to the rock-shaft 9^a. By this construction and arrangement the movement of the wheel 8, from the full line to the left-hand dotted line positions (see Fig. 1), through the connecting parts 9^a, 9^b, 9^c, 17' and 17 depresses the latch 16, as described. In order to permit this leftward movement of the roller 8, the drum 3 is provided with parallel circumferential grooves 3^x (see Figs. 1 and 5), into which the flanges 8' of the roller 8 drop a sufficient distance to effect the rocking of shaft 9^a and the depression of the latch 16 as described.

30 During the operation of the machine, as long as the tubes or bags 4 are being fed with the proper regularity, the roller 8 is limited in its movements to the full line position shown in Fig. 1. In other words, as long as one of the tubes 4 is passing between the drum and the roller 8, the said roller travels over the outer face of the tube and cannot enter the grooves 3^x. When, however, the operator misses feeding one or more of the tubes, the portion of the drum which is rotating past the roller 8 becomes bare, and the roller instantly gravitates toward the left and engages the said grooves. This effects the depression of the latch 16, as described, and prevents the cam 14^a from rocking the lever 15 as shown in Fig. 4. The lever 15 being thus held rigid by the latch 16 the next engagement of the cam 14^a with the lower end of said lever effects the leftward movement of the sleeve 14 on the shaft 11 and collar 11^c against the tension of the spring 14^b. This movement of the sleeve 14 withdraws the wedge 13 from the corresponding portion of the slot 11^b in the arm 11^a of the paste pad, and at the same time moves the wedge 13' towards the left at the opposite side of the shaft 11, which action forces the paste pad towards the shaft 11 sufficiently to miss contact with the paste roll 12. The parts are then held in the last described position while the paste pad is being rotated by the shaft 11 towards and past the pasting position indicated at 3^a in Fig. 1. This shortening of the stroke 65 of the pad 11' by the wedge 13' is sufficient to allow the said pad to traverse the pasting position 3^a without touching the drum 3. The dotted lines in Fig. 1 and the full lines in Fig. 4 show the extension and contraction of the pad 11', and the clearance 70 between the pad and the drum, for preventing the paste carried by the pad 11' from reaching and fouling the drum, during the intervals in which the roller 8 is traversing the grooves 3^x of the drum. When the feeding 75 of the bag-tubes is resumed, the tubes passing between the drum 3 and the roller 8 restore the latter to the full line position, shown in Fig. 1. This effects the upward tilting of the latch 16, and again allows the 80 lever 15 to be rocked back and forth idly by the cam 14^a, as shown by the full and dotted lines in Figs. 2, 3 and 5. In practice the contraction of the pad 11' becomes effective while the pad is approaching the 85 roller 12 (see full lines Fig. 1) to receive a fresh supply of paste. In Fig. 4 the full line position of the pad 11' corresponds to the dotted position of the said part in Figs. 1 and 5, and shows that the pad has been 90 rotated one half turn and that the wedges 13 and 13' have exchanged positions. The arrows show the direction of travel of certain of the parts, and the dotted lines in Fig. 1 show the progress of the paper tubes 4, from 95 the time they pass the pasting position 3^a, until they leave the drum and pass between feed rolls 18—18', and on to a pair of press rolls 19—19', from which the finished bags are discharged. Between the pasting position 3^a and the roll 18, the bottoms of the bags are operated upon by the usual creasing and flap-folding mechanisms, the detailed descriptions of which are omitted, because they form no part of the present invention. 100

Having thus described my invention, what I claim is—

1. In a paper bag bottoming machine, the combination of the drum having circumferential grooves, and the slitting rolls which carry the paper bags to the drum, one of said rolls having a spur which pierces and effects the spreading of the bottom end flaps after the slitting operation, of a rotary paste pad 110 geared to and driven by said drum adapted to apply paste to said end flaps while the bags are being carried by the drum past a certain point, a roller adapted to engage the grooves in the drum whenever the feeding of the unpasted bags is interrupted, and means actuated by said roller for preventing the said pad from smearing the drum with paste. 115

2. In a paper bag bottoming machine, the combination of the drum having circumferential grooves, and a pair of slitting rolls, one of said rolls being in operative engagement with the drum and having a spur which pierces and effects the spreading of 120 130

- the bottom end flaps of the bags, of a rotary paste pad geared to and driven in unison with the drum adapted to apply paste to the said flaps while the bags are passing a certain point, a roller disposed near the drum and adapted to engage said grooves when the feeding of the bags is interrupted, said roller being withheld from said grooves as long as the feeding of the bags is regular, and means for preventing the said pad from daubing the bare drum with paste.
3. In a paper bag bottoming machine, the combination with the feed and slitter rolls, and a drum adapted to carry the bags during the bottoming operations, of a roller movable towards and from said drum adapted to engage the bottom end flaps and to force and hold said flaps against the drum while the bottoms of the bags are being partially folded, means for applying paste to the bottom ends of the bags after the partial folding thereof, and means actuated by the extreme movement of said roller towards said drum for preventing the smearing of the drum with paste during the intervals in which the feeding of the unpasted bags to the drum is interrupted.
4. In a paper bag bottoming machine, the combination with a drum adapted to carry the bags during the bottoming operation, of a rotary pasting device geared to the drum adapted to apply paste to portions of the bottoms of the bags while the bags are being carried past a certain point, a roller normally riding on the drum in the path of the bags, a rock shaft for supporting said roller, and means actuated by said rock shaft for preventing said device from daubing paste on the circumference of the drum whenever the feeding of the bags is interrupted.
5. In a paper bag bottoming machine the combination of a pair of feed-rolls into which the paper tubes comprising the bags are fed, a pair of slitter rolls adapted to slit the bottom ends of the tubes for providing end flaps, and a mechanism for partially folding the bottom ends of the bags after they leave the slitter rolls, a drum adapted to receive the tubes from the slitter rolls and to carry them towards a pasting position, an adjustable rotary pad adapted to apply paste to the bottom end flaps at the pasting position, a shaft for supporting and rotating said pad, a sleeve slidable on said shaft adapted to vary the strokes of said pad, a cam carried by said sleeve, a lever disposed in the path of said cam adapted to be rocked by the cam during the regular feeding of the said tubes, means for holding said lever rigid for effecting the endwise movement of said sleeve for preventing said pad from daubing paste on the bare drum whenever the orderly feeding of the tubes is interrupted, and a roller riding on the drum in the path of the tubes adapted to control the operation of said lever.
6. In a paper bag bottoming machine, the combination with the drum which carries the bags during the bottoming operations, of an adjustable rotary paste pad adapted to apply paste to the bags as the drum carries them past a certain point, a shaft for supporting and driving said pad, a sleeve slidable on said shaft, means carried by said sleeve for lengthening and shortening the strokes of said pad, a lever adapted to move said sleeve in the direction for shortening the stroke of said pad, tension means for operating said sleeve in the opposite direction, a latch adapted to prevent the rocking of said lever, and a roller riding on said drum adapted to effect the operation of said latch.
7. In a paper-bag bottoming machine, the combination with the drum adapted to carry the tubes comprising the bags during the bottoming operation, a roller normally riding on said drum, means for spreading portions of the bottom end of each tube before it reaches said roller, means for swinging said roller away from the drum in advance of said spreading operation, means for moving said roller in the opposite direction for pressing the tubes against the drum, means for partially folding the bottom end of the tube, a pasting device adapted to apply paste to the bottom end of the tube after the partial folding is effected, and means actuated by the extreme movement of said roller towards the drum for preventing the paste from fouling the face of the drum whenever the orderly feeding of the tubes is interrupted.
8. In a paper bag bottoming machine, a drum adapted to carry the paper tubes comprising the bags during the bottoming operations, means for slitting the bottom ends of the tubes for providing foldable end flaps, means for partially folding the bottom ends of the tubes, means for spreading said end flaps before said partial folding, a roller adapted to press the tubes against said drum during the folding operations, means for moving said roller away from the drum in advance of the spreading operation to allow the spread flaps to pass between the roller and the drum, means for applying paste to the said flaps after the folding operation, and means controlled by said roller for preventing the daubing of the drum with paste whenever the feeding of the tubes is interrupted.
9. A paper bag bottoming machine including a drum adapted to carry the flat tubes comprising the bags during the bottoming operations, a shaft geared to and driven by said drum, a paste pad mounted on and rotat-

ed by said shaft, said pad having a radial arm provided with a slot to receive said shaft, a sleeve slideable on said shaft, wedges carried by said sleeve and disposed in the slot of said arm at the opposite sides of said shaft adapted when said sleeve is reciprocated to move said pad towards and away from said drum, a lever adapted to be rocked by said

sleeve while the tubes are being fed regularly into the machine, and means for holding said lever rigid for operating said sleeve in the direction for preventing said path from daubing the paste on the bare drum whenever the feeding of said tubes is interrupted.

In testimony whereof I affix my signature. 15
JOSEPH W. TAGGART.
